PROCESS OF PRODUCING FINISHES
IMITATIVE OF STONEHarry Cohen, Galion, Ohio, assignor to The Per-
fection Steel Body Company, Galion, Ohio, a
corporation

Application July 11, 1934, Serial No. 734,675

4 Claims. (Cl. 91—68)

This invention appertains to the art of applying finishes to articles of manufacture in simulation of the natural appearance of different kinds of stone, and particularly to a process of providing a finish of this sort in imitation of marble.

It is known that because of the peculiar strata formation of marble such stone is perhaps the most difficult to imitate in natural formation and natural colors. One of the problems, for instance, in the production of an imitation marble finish lies in the difficulty of duplicating certain irregular streak-like formations that occur in the original or natural marble. These streak-like formations, as well as certain scattered spotty formations are generally comparatively light as occurring in different colored marbles running from the lighter to even the most dark colors.

A primary object of this invention, therefore, has been to devise a process which will be conducive to obtaining more natural-like imitation effects or marble finishes than heretofore secured by any processes of which I have knowledge.

In the carrying out of my finishing process, I avail of suitable applicator means for the paint, lacquer, or other coloring matter employed, preferably some suitable sort of spraying device. Such a device is excellent for varying the depth of the color applied to the base operated upon and even for producing high light effects, but even by the use of an applicator instrumentality of this type, or brushes, I have found it almost impossible ordinarily to imitate the light streaky or spotty formations that occur in natural marble as commercially produced today. I have discovered however, that these particular effects which I refer to may be obtained in considerable degree of closeness of the simulation of the natural stone by applying to the base being finished moisture in the form of water, in a peculiar manner and then causing the paint, lacquer, or coloring matter to be applied to the base in such a manner that by reason of the applied moisture the pigment or coloring matter will not adhere to those portions of the base moistened in the manner stated.

Now in the carrying out of my invention, if the base being finished for obtaining a marbleized effect is relatively light in color, either naturally or by reason of the application of a light coat of lacquer or the like, it will be evident that by moistening certain portions of this base, and then applying other imitation coats of coloring matter at the portions moistened, the said base will receive the finish of the coloring matter with permanent application thereof only in such places as do not carry the moisture. Thereupon, after subsequent

drying of the base processed for finishing by the process of the invention, the parts of the article being produced with the marbleized effect, which are moistened at the time of the application of the paint or lacquer, etc., will remain of the same color as originally possessed thereby. It is this action of the moisture in conjunction with the paint which is availed of for the purposes of my invention, though it is contemplated in my process that I shall subject the moisture, as for instance a drop or drops of water deposited on the base, to a scattering action in order to obtain the desired imitative results, as will be more fully presented hereinafter.

The figure of the drawing is illustrative of a piece of material which may be any suitable article of manufacture, the surface of which is finished in a manner to resemble the surface of a slab or section of marble, employing the process of my present invention.

Describing specifically the process which I have devised for the purposes of my invention, as above outlined briefly, and referring to the illustration of the drawing, it is contemplated that the base or article to which my finish may be applied shall be supplied with a base coating of paint, lacquer, or coloring matter. In the present instance, this coating, showing at 1, in various portions of the drawing, is of light color. Other finishing coatings in imitation of marbleized effects will be applied to the said base coat of paint 1 for the purpose of producing the shadow-like formation 2 that occurs in marble slabs and for providing other shaded effects such as may be designated at 3. It is impossible in a black and white drawing, of course, to depict the actual marble formation so that this is not particularly attempted by the illustration of the accompanying drawing, the primary object being to illustrate the manner in which the streak-like formations 1 appearing in the drawing are formed.

After the base coat of light coloring matter has been applied to the base or article which is being treated by the finish of my invention, and has dried, I cause to be deposited upon the base or surface being finished, on the said base coat 1, a drop or drops of water. Other liquids may possibly be used for the purposes of my invention, but water provides a very satisfactory liquid for the purpose.

Thereupon, the drop or drops of water will be subjected to the action of pressure preferably in the form of an air spray directed against the water causing the same to be scattered over

the surface being treated to provide spot formations *1a* of different sizes and irregular shapes and continuous streak-like or line formations designated *1b* in the drawing. These 5 spot-like or streak-like or line formations represent moistened portions of the base coating *1*, previously referred to, and their appearance in simulation of marbleized effects does not become apparent until a subsequent coat or coats 10 of paint or coloring matter is superposed upon the base or article being finished by being applied whilst the moistened portions *1a* and *1b* are still moist.

My invention avails of the known fact that 15 when a base or other article is provided with moisture or water thereon, the moistened portions will not provide an adherent surface for paint or lacquer or light coloring matter, if the latter shall be applied to the base, while 20 said portions are in their moistened condition.

It has been found in practise, oddly as it may seem, that the subjecting of a drop or drops of water to the action of a pressure force like sprayed air will cause such a scattering or 25 movement of the water on the surface as to create very close simulation of light strata formations for imitation marble effects.

It will be understood that after the base is moistened in the manner described above, and 30 a subsequent coat or coats of paint, lacquer, or the like, applied, while the portions *1a* and *1b* are in moistened condition, the subsequent coats of coloring matter will adhere to the base at all portions except where the latter 35 is moistened and the base may be dried in the air or subjected to heat in order to be dried after the coats of coloring matter superposed upon the moistened base are applied, drying, of course, being to eliminate the moisture. Generally speaking, in the spraying operation, the 40 sprayed paint or lacquer will adhere and immediately dry on all portions of the surface except those that are moistened in the manner set forth. It is not necessary under certain 45 applications of the process of the invention, where certain imitative effects are to be produced, that any base coat of paint whatsoever be applied to the base or article of manufacture being treated. Sometimes the natural color of 50 the base, either metal, composition, or the like, may be quite suitable to afford the color of a certain object to be imitated under which conditions the drop or drops of water which I use, and which are subjected to pressure of being 55 shattered into spot formations and streak-like or line formations, may be applied directly to the substance from which the base or article of manufacture may be made, and when subjected to the scattering effect described, will 60 accomplish the desired result of preventing a subsequent coat or coats of paint, or coloring matter, from adhering to the moistened portions.

If necessary, at the conclusion of the process 65 of the invention, drying of the moistened spots, streaks, or lines, formed by the water drops subjected to pressure, may be accomplished by wiping the article of manufacture. I do not wish, therefore, to be limited to any particular method 70 of drying, as any one method is not material to the invention.

A convenient way in which to cause the drop 75 or drops of water, or liquid, used to moisten the base or article in the manner specified to spread

with streak-like or continuous line effects, is to direct the pressure means such as the air spray toward the liquid in a plane approximately parallel with the plane of the surface being treated.

Any suitable apparatus may be employed to 5 deposit the water, or liquid, used for the moistening purposes described, upon the surface being treated, and under certain conditions, if this water is permitted to drip from a point at some distance from the surface of the article of 10 manufacture, the splashing of the water may be availed of to provide drop-like effects in addition to the application of air pressure for scattering the moisture along with the streak-like action or continuous line effects.

Having thus described my invention, what I 15 claim as new and desire to secure by Letters Patent of the United States, is:—

1. The process of producing imitative effects in the finishing of articles of manufacture which 20 consists in applying to a base to be treated with an imitative finish a small quantity of a masking liquid, subjecting said liquid as applied superficially to the base to pressure to cause the same to be moved to different portions of the base to 25 be masked, and whilst the said different portions are subject to the moisture of the liquid applying to the base a coat or coats of coloring matter which does not adhere to the masking liquid.

2. The process of finishing a base or article 30 of manufacture in imitation of stone such as marble, which consists in applying to the base a drop or drops of water for masking parts of the base, subjecting said water to pressure to scatter the same to provide moistened spots or 35 streak-like portions on the surface of the base to be masked, and then applying to the base while said spots and portions are moist a super- 40 posed coating of coloring matter which does not adhere to the masking liquid.

3. The process of treating articles of manufacture to provide finishing effects in imitation of marble, or the like, the same consisting of applying to the base a preliminary coat of coloring matter, depositing upon said coat of coloring 45 matter a small quantity of a masking liquid, subjecting said liquid to the action of an air spray to scatter the liquid to different spots or portions of the colored surface to be masked, and while said spots or portions are moistened applying to the said surface a subsequent coating of coloring matter which does not adhere to the masking liquid and is prevented from adhering to the surface by the moisture on said spots or 50 portions.

4. The process of treating articles of manufacture to provide finishing effects in imitation of marble, or the like, the same consisting of applying to the base a preliminary coat of coloring 55 matter, depositing upon said coat of coloring matter a small quantity of a masking liquid, subjecting said liquid to the action of an air spray directed to the drop or drops of liquid in a plane approximately parallel with the plane of the surface being treated, to scatter the liquid to different spots or portions of the colored surface to be masked, and while said spots or portions are moistened applying to the said surface a subsequent coating of coloring matter which does not 60 adhere to the masking liquid and is prevented from adhering to the surface by the moisture on said spots or portions.
